CLAIM

The ornamental design for a printer for tattoo, as shown and described.

DESCRIPTION

FIG. 1 is a bottom perspective view of the printer for tattoo showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom perspective view showing the state in which the upper cover has been closed.

The broken lines depict portions of the printer for tattoo that form no part of the claimed design. The dash-dot broken lines define the boundary of the claimed design and form no part thereof.

1 Claim, 8 Drawing Sheets(56)
